CLAIM

The ornamental design for a golf club head, as shown and described.

DESCRIPTION

FIG. 1 shows a front view of a golf club head showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, rear and left side perspective view thereof;

FIG. 8 shows a bottom, rear and right side perspective view thereof.

FIG. 9 shows an A—A cross-section view thereof; and,

FIG. 10 shows a B—B cross-section view thereof.

The broken line showing of the shaft insertion hole is included for the purpose of illustrating and forms no part of the claimed design.
